S. KARPEN & BROS., OF CHICAGO, ILLINOIS, A CORPORATION OF WEST VIRGINIA.

SOFA-BED, &c.

1,261,547.

Specification of Letters Patent.

Patented Apr. 2, 1918.

Application filed September 10, 1915. Serial No. 49,909.

To all whom it may concern:

Be it known that we, MARTIN S. KARPEN and CHARLES HULTGREN, citizens of the United States, residing at Chicago, in the county of Cook and State of Illinois, have invented new and useful Improvements in Sofa-Beds, &c., of which the following is a specification.

This invention relates, particularly, to 10 combined sofas and beds, or combined couches and beds, and the primary object is to provide a device of improved construction and operation.

The invention is illustrated in its preferred embodiment in the accompanying drawings, in which—

Figure 1 represents an end view of the improved structure in unfolded condition, one of the end-standards being removed, and 20 a rear frame member employed being shown in section; Fig. 2, an enlarged broken horizontal sectional view, taken as indicated at line 2 of Fig. 1, illustrating the means whereby the seat is revolvably mounted in the frame; Fig. 3, a broken vertical section, taken as indicated at line 3 of Fig. 1; Fig. 4, a view similar to Fig. 1, but showing the structure in sofa form; Fig. 5, a broken sectional view, taken as indicated at line 5 25 of Fig. 7; Fig. 6, a similar view, showing the bed-frame in folded condition; Fig. 7, a broken horizontal sectional view, taken as indicated at line 7 of Fig. 1; Fig. 8, a broken vertical sectional view, taken as indicated at line 8 of Fig. 1; Fig. 9, a broken sectional view similar to Fig. 5, but showing a modification of the truss-controlling device; and Fig. 10, a broken sectional view, similar to Fig. 6, but showing the modification shown 40 in Fig. 9.

Referring to Figs. 1 to 8, inclusive, the preferred embodiment comprises a frame A having end-standards A¹, which provide the arms for the sofa, and having a longitudinal rear frame member A² detachably connected with the end-standards; a swingingly-mounted back B, whose lower edge is normally locked over the rear portion of the seat, the back being capable of movement to 45 permit reversal of the seat; a seat C reversibly mounted in an improved manner in the frame A; and an improved folding bed D, carried in the lower portion of the seat-frame and normally housed beneath the seat 50 when the structure is in sofa form.

The frame A may be of any suitable construction. In the construction illustrated, the end-standards A¹ may be made as ornamental as desired. The lower rear connecting member A² is equipped with attaching devices 1, having hook-portions which detachably engage screws, or studs, 2, secured to the end-standards. 60

The back B is connected by hinges, or flexible strips, 3, with an upper rear frame member 4, which may be detachably connected, in any suitable manner, to extensions 5 of the end-standards A¹. The back B is provided near one of its hinges with a clip 6, to which is connected a link 7, whose lower end is provided with a stud 8, which engages a slot 9 in a member 10 attached to an end-standard. The slot 9 has an off-set, or recess, 9^a at its upper portion, which may be engaged by the stud 8 when the back is to 75 be held in an elevated position.

The seat C comprises a frame, having end members 11, a front connecting member 12, a rear connecting member 13, and braces 14 joining the members 12 and 13; and a cushion 15, which may be provided with the usual upholstering springs (not shown). 80

The mounting for the seat C comprises a pair of frame-carried plates 16, applied to the inner surfaces of the end-standards A¹; 85 and a pair of seat-attached plates 17 secured to the end members 11 of the seat-frame, and equipped with studs, or rollers, 17^a, 17^b, which work in cam-slots 16^a, 16^b, with which the plates 16 are provided. 90

As appears from Figs. 2 and 3, the plates 16 are separated from the inner surfaces of the end-standards A¹ by spaces 18. This is preferably accomplished by providing the plates 16 with outwardly-struck perforate 95 bosses 19, which accommodate screws 20, which serve to secure the plates to the end-standards. The rollers 17^a and 17^b are attached to the plates 17 by pivot-studs 21, and the rollers have flanges 22 which are 100 confined between the plates 16 and the end-standards A¹, while the plates 17 are disposed close to the inner surfaces of the plates 16. Thus, the seat really serves as a spacing and connecting member between the 105 end-standards A¹, notwithstanding the movability and free reversibility of the seat.

The seat may be turned to the inverted position by swinging the rear portion of the seat upwardly and forwardly, as indicated 110

by the arrow in Fig. 4, the back being first swung out of the way. In reversing the seat, the roller 17^a travels in the vertical slot 16^b, which bisects the horizontal slot 16^a, while 5 the roller 17^b travels on the lower wall of the slot 16^a. In both the upright and inverted positions, the rollers 17^a and 17^b rest upon the bottom walls of the slots 16^a, thus holding the seat in stable condition. This 10 construction, while providing for the easy reversibility of the seat, renders unnecessary the use of catches or locking devices for holding the seat in either the normal upright position or the inverted position.

15 The folding-bed B preferably comprises a section 23 fixedly secured to the bottom portion of the seat-frame and constituting a rear bed-section; and a section 24 having hinge-connections with the section 23 and 20 constituting a front bed-section.

The section 23 is U-shaped and comprises a longitudinal member 23^a and end-members 23^b. To the extremities of the members 23^b are securely attached hangers, or hinge-members, 23^c, which, when the structure is in sofa-form, depend from the rear corners of the sofa-seat. The section 24 is U-shaped and comprises a longitudinal member 24^a, and end-members, 24^b. The extremities of 25 the arms, or members, 24^b, have rigidly secured thereto short arms, or hinge-members, 24^c, the extremities of which are connected with the hinge-members 23^c, by pivots 25. The extremities of the end-members 23 afford shoulders 26; and the extremities of 30 the end-members 24^b afford shoulders 27 (Fig. 6), which abut against the shoulders 26 when the bed is extended.

40 The end-members of the section 24 have pivotally connected therewith legs 28, which are joined by links 29 to pivots 30 carried by ears 31, with which the hinge-members, or hangers, 23^c, are provided. The arrangement is such that the legs will be automatically folded and unfolded in the operations 45 of folding and opening the bed, respectively.

At the joint between the sections of the bed-frame is disposed a U-shaped truss 32. The extremities of this member are preferably joined, by pivotal connections 33, to the extremities of the end-members 24^b of the front bed-section. The longitudinal portion of the truss-member is connected, by links 34, to the seat-frame. In the illustration given, the links 34 are pivotally connected with clips 35 carried by the brace-members 14, and are loosely joined by a pin 36 to the central portion of the truss-rod. It will be noted that the truss-rod 32 is elevated from the position shown in Fig. 5 to the position shown in Fig. 6 when the bed-frame is folded. The links 34 permit this movement, but serve at all times to keep the truss-rod substantially within the confines 65 of the seat-frame, so that the truss-rod will

not get out of position when the seat is swung to the normal upright position shown in Fig. 4. The bed-frame is maintained in the folded condition by a catch 37 carried by the member 12 of the seat-frame. The catch 70 37 may be of the usual construction, being capable of turning in a bearing 38 applied to the member 12.

The folding-bed frame is equipped with the usual flexible wire mattress, or spring 75 bed-bottom 39.

It will be noted from Fig. 4 that the cushion 15 of the seat is disposed mainly in front of the longitudinal seat frame member 13, and it will be understood that 80 where upholstering springs are employed they will be disposed in front of the truss-rod 32, so as not to interfere with the operation of the truss-rod.

When it is desired to convert the structure 85 from sofa-form to bed-form, the sofa back B is swung to the position shown in Fig. 2 and the seat is then reversed by swinging the rear edge of the seat upwardly and forwardly. The bed can then be unfolded by releasing the section 24 from the catch 37 and swinging the section 24 to the open position, in which operation the legs 28 are extended. By providing the bed-sections 23 and 24 with either arms, or off-set 90 hinge-members, 23^c, and 24^c, a simple construction is afforded; and room is provided, in the folded condition of the bed, for the bedding, which, as is usual in this class of construction, is folded in the operation of 100 folding the bed.

After the bed is opened, the back B may be lowered to rest against the member 12.

The construction described is simple, cheap, durable and capable of being operated with the greatest facility.

The foregoing detailed description has been given for clearness of understanding only, and no unnecessary limitation should be understood therefrom, but the appended 110 claims should be construed as broadly as permissible, in view of the prior art.

What we regard as new, and desire to secure by Letters Patent, is—

1. In a structure of the character set 115 forth, the combination of a frame, a seat reversibly mounted therein, a bed-section fixedly secured to the lower portion of the seat-frame, hangers depending from the rear corners of the seat-frame, a bed-section 120 having upwardly-extending members pivotally connected with said hangers, a truss pivotally connected with said second-named bed-section near the points of connection with said hangers, and connecting means between the seat frame and truss for maintaining the truss in properly housed position.

2. In a structure of the character set 130 forth, the combination of a frame, a reversi-

bly mounted seat, a rear bed-section fixedly secured to the lower portion of the seat-frame, hangers depending from said bed-section, a front bed-section equipped with 5 upwardly-extending arms pivotally connected with said hangers, a truss pivotally connected with the extremities of the end-members of said front bed-section, and con-

necting means between said truss and seat frame for maintaining the truss in properly 10 housed position.

MARTIN S. KARPEN.
CHARLES HULTGREN.
